UNITED STATES PATENT OFFICE.

EDWIN ALLEN BARDWELL, OF SHELBURNE FALLS, MASSACHUSETTS.

DESIGN FOR A NAIL-SET.

44,834.

Specification for Design.

Patented Nov. 4, 1913.

Application filed September 8, 1913. Serial No. 788,750. Term of patent 7 years.

To all whom it may concern:

Be it known that I, EDWIN ALLEN BARDWELL, a citizen of the United States, residing at Shelburne Falls, in the county of Franklin and State of Massachusetts, have invented a new, original, and ornamental Design for Nail-Sets, of which the following is a specification, reference being had to the accompanying drawing, forming part thereof.

The figure is a plan view of a nail set showing my new design.

I claim;

The ornamental design for a nail set, as shown.

EDWIN ALLEN BARDWELL.

Witnesses:

CLIFTON L. MCKNIGHT,
JOHN H. SHIPPEE.
